United States Patent Office

Des. 208,337
Patented Aug. 15, 1967

208,337

XEROGRAPHIC DOCUMENT REPRODUCING APPARATUS OR SIMILAR ARTICLE

Roger H. Eichorn, Webster, N.Y., assignor to Xerox
Corporation, Rochester, N.Y., a corporation of New
York

Filed Oct. 22, 1965, Ser. No. 87,766

Term of patent 14 years

(Cl. D61—1)

FIG. 1

FIG. 2

FIG. 3

FIG. 4

FIG. 5

FIG. 6

FIG. 1 is a front and right-side perspective view of a xerographic document reproducing apparatus or similar article showing my new design;

FIG. 2 is a left-side elevational view thereof;

FIG. 3 is a rear elevational view thereof;

FIG. 4 is a right-side elevational view thereof;

FIG. 5 is a top plan view thereof;

FIG. 6 is a front view thereof.

I claim:

The ornamental design for a xerographic document reproducing apparatus or similar article, as shown.
